R. L. JOHNSON

PLOW

Filed Sept. 20, 1921

UNITED STATES PATENT OFFICE.

ROBERT L. JOHNSON, OF ATMORE, ALABAMA.

PLOW.

Application filed September 20, 1921. Serial No. 501,928.

To all whom it may concern:

Be it known that I, ROBERT L. JOHNSON, a citizen of the United States, and a resident of Atmore, in the county of Escambia and 5 State of Alabama, have invented certain new and useful Improvements in Plows, of which the following is a specification.

My invention relates to improvements in plows, and has for its object to provide an 10 improved plow which is adapted to perform the various earth working operations without requiring several different types of plows, and which is of simple and durable construction, reliable in operation and easy 15 and inexpensive to manufacture.

Other objects and advantages of the invention reside in certain novel features of construction, combination and arrangement of parts which will be hereinafter more fully 20 described and particularly pointed out in the appended claims, reference being had to the accompanying drawings forming part of this specification, and in which:

Figure 1 is a perspective view illustrating 25 the invention adapted to perform the function of the turn or mold board plow;

Figure 2 is a detail perspective view of a mold board;

Figure 3 is a similar view of the point;

Figure 4 is a similar view of the runner; 30 Figure 5 is a similar view of the brace;

Figures 6, 7, 8 and 9 are perspective views of diverse forms of shovel plows adapted to be selectively employed in conjunction with 35 the present invention; and

Figure 10 is a view illustrating the harrow adapted to be employed with the present invention.

Figure 11 is a fragmentary view, partly in 40 elevation and partly in vertical section, showing the construction of the plow standard.

Referring to the drawings wherein for the sake of illustration is shown the preferred embodiment of the invention, the numeral 10 designates the plow beam, having a clevis 11 at its forward end and having handles 12 connected thereto. A standard 13 depends from the beam and is braced by 45 means of a brace 14. The standard 13 is provided with transverse bolt holes 15 and longitudinal bolt holes 16, the transverse bolt holes being arranged adjacent the lower end of the standard and the longitudinal bolt holes being arranged above the trans- 50 verse bolt holes.

The mold board or turning plow employed in this invention is of a special construction, and as shown in Figures 1 to 4 inclusive comprises a runner 17 taking the form of a three sided polygon and converging toward its forward end. One side of the runner is curved and is formed to constitute a cutting edge, as indicated at 18. The mold board is arranged on the runner and consists of a curved plate 19 having an inturned flange 20 along its lower side which rests upon the runner. The mold board and its flange 20 are curved correspondingly to the curved cutting edge 18 of the runner, and the mold board is spaced slightly from this edge. The runner and the flange 20 are provided with registering bolt holes, indicated at 17^a and 20^a, respectively, through which bolts or other fastenings are extended to secure the mold board in the runner. A brace 21 is also provided and has one end secured to the curved plate 19 constituting the mold board and has its other end secured to the runner. At its forward edge the mold board is provided with an offset flange 22 constituting a seat. A point 23 has a portion received on the seat and secured thereto by rivets 24, the point 23 having a cutting edge 25 and having a flange 26 provided with a cutting edge 27 and engaging under the forward edge of the runner. The flange 26 is complementary in its action to the action of the runner serving in this respect as an auxiliary runner for the projecting portion of the point 25. Connecting means are provided for securing the turning plow to the standard 13 and preferably consists of a connecting bar 28 having bolts 29 connecting it to the mold board and bolts 30 extending through the cross bar and through the transverse bolt holes 15 provided in the standard. 55

When it is desired to use a sweep shovel or heel scraper the mold board or turning plow is detached and one of the earth working elements shown in Figures 6, 7, 8 or 9 is employed. It is to be noted that all of these elements include a connecting portion, designated at 31, 32, 33 and 34, the connected portions having bolt holes 35, 36, 37 and 38, respectively, the bolt holes being adapted to receive a bolt which also passes through the longitudinal bolt hole 16 of the standard 13. A harrow designated at 40, may also be employed in lieu of the other earth working elements, the harrow having for this purpose a connected bar 41 provided with 60 65 70 75 80 85 90 95 100 105 110

a bolt hole 42 adapted to receive the bolt extending through the longitudinal bolt holes 16 of the standard 13 whereby the harrow is connected to the standard.

5 In this manner any desired type of earth working element may be utilized with the same plow stock by simply attaching it to the plow standard. One of the important features of the invention is the form of 10 mold board plow or earth working element which permits this type of earth working element to be utilized with a stock susceptible of employment in conjunction with the other types of earth working elements.

15 I claim:

1. In a plow, a standard having longitudinal bolt holes, a runner comprising a flat plate converging toward its forward end and having a curved knife edge, a mold 20 board consisting of a curved plate having a flange resting on the runner and secured thereto and an offset flange at its forward

end constituting a seat, the mold board having a curvature corresponding to the curved edge of the runner, a point having a portion 25 received on said seat and secured thereto, a brace connecting said runner and said mold board, a connecting bar secured at one end to said mold board and having bolt holes at its other end registering with the bolt holes 30 of the standard, and bolts extending through said registering bolt holes.

2. In a plow, a runner comprising a flat plate converging toward its forward end and having a curved knife edge, a mold board 35 consisting of a curved plate having a flange resting on the runner and secured thereto and an offset flange at its forward end constituting a seat, and a point having a portion received on said seat and secured thereto and having a cutting edge and a flange complementary to the runner.

ROBERT L. JOHNSON.
